UNITED STATES PATENT OFFICE.

SANGUINET H. BENOIST, OF ST. LOUIS, MISSOURI.

CUFF-BUTTON, &c.

SPECIFICATION forming part of Letters Patent No. 257,644, dated May 9, 1882.

Application filed March 22, 1892. (Model.)

To all whom it may concern:

Be it known that I, SANGUINET H. BENOIST, of the city of St. Louis, in the State of Missouri, have invented a certain new and useful Improvement in Non-Separable Cuff-Buttons, &c., of which the following is a full, clear, and exact description, reference being had to the accompanying drawings, forming part of this specification.

10 My invention relates to a sliding shoe-piece; and it consists in the points of construction hereinafter set forth, the object of my invention being to form a cheap, strong, and durable button, the shoe-piece of which can be thrown 15 into a position relative to the head for the easy insertion of the head through the button-holes, and then be thrown back and retained in its natural or wearing position.

In the drawings, Figure 1 is a top perspective view. Fig. 2 is an under perspective view. Fig. 3 is a vertical section, showing the shoe-piece slid back for the easy insertion of the button-head through the button-holes; and Fig. 4 is a similar section, showing the parts 25 in wearing position. Fig. 5 is a section on line 5 5, Fig. 4. Fig. 6 is a diagram of the blank for forming the shoe-piece. Fig. 7 is a view of the shoe-piece formed.

A represents the button-head, the face of 30 which may be plain, as shown, or it may be formed to receive a set. The under part of the head has inturned flanges *a*, which form side grooves, *a'*, in which the part *b* of the button-shank *B* slides.

35 *B'* is the shoe on the end of the shank. *b'* is the spring-catch, which passes through a hole, *b²*, in one end of the button-head to hold the parts in wearing position.

When the button is to be put on the cuff, 40 &c., the spring-catch is pushed down, which releases it, and the shoe-piece is then slid

back until the shank reaches the other end of the button-head. (See Fig. 3.) The button-head is then put through the button-holes—from the inside, of course—and the shoe-piece is then 45 slid back to its wearing position, when the spring-catch will engage the end of the button-head, as shown.

I prefer forming the shoe-piece out of one piece of thin metal, as stated and shown.

50 In Fig. 6, *B'* represents the part of the blank which forms the shoe; *B B'*, the parts which form the shank; *b b*, the parts which form the part of the shank within the flanges *a*, and *b'* the tongue which forms the spring. The end 55 of the tongue is turned over to form the catch or head of the spring.

b³ is a slot in the under part of the piece *b*, to allow the spring to work.

b⁴ are the notches in the blank which receive 60 the flange of the button-head.

The points of folding of the blank are shown by dotted lines.

I claim as my invention—

1. In a removable button or stud for cuffs, &c., the combination of the head *A* and shoe-piece *B B' b*, sliding in the inner face of the head to and from the end thereof, substantially as and for the purpose set forth.

2. In a removable button or stud for cuffs, &c., the combination of head *A*, with grooves *a'* and orifice *b²*, and the sliding shoe-piece *B B' b*, with spring-catch *b'*, constructed and operating substantially as set forth.

3. The shoe-piece *B B' b b'* for cuff-buttons, 75 formed of a single plate of metal folded together substantially as shown and described.

SANGUINET H. BENOIST.
